Primary Examiner—Raphael Barkai*Assistant Examiner*—Mitchell I. Siegel*Attorney, Agent, or Firm*—Westman, Champlin & Kelly, P.A.**[57] CLAIM**

The ornamental design for a sectioned pool cue, as shown and described.

DESCRIPTION

FIG. 1 is a side elevational view of a sectioned pool cue, embodying my new design, all other side being identical; FIG. 2 is a left end elevational view thereof; FIG. 3 is a right end elevational view thereof; and, FIG. 4 is an enlarged fragmented side elevational view of the tip portion of the sectioned pool cue for clarity of illustration.
